UNITED STATES PATENT OFFICE.

ALBERT P. FULMER AND FRANK M. NEBINGER, OF WILMINGTON, DELAWARE.

HOOK AND EYE.

1,076,360.

Specification of Letters Patent. Patented Oct. 21, 1913.

Application filed April 30, 1912. Serial No. 694,065.

To all whom it may concern:

Be it known that we, ALBERT P. FULMER and FRANK M. NEBINGER, citizens of the United States, residing at Wilmington, in the county of Newcastle and State of Delaware, have invented new and useful Improvements in Hooks and Eyes, of which the following is a specification.

The invention relates to separable fasteners and has for an object to provide a hook and eye.

The invention embodies, among other features, a device comprising a hook member and an eye member, the said members being adapted for independent connection with apparel and adapted to coöperate by their mutual relative engagement to connect the portions of the apparel to which the respective members are secured, the said members being movable to relatively lock, and easily movable into disengaged position by a slight pressure of the finger on the mentioned members.

A further embodiment of the invention resides in a hook member formed of a single piece of material and an eye member likewise formed of a single piece of material, the hook member being provided with integral means for guiding the eye member into locked engagement with the hook member, suitable attaching means being formed integrally with the said members for independently securing the same to apparel.

In the further disclosure of the invention reference is to be had to the accompanying drawings constituting a part of this specification, in which similar characters of reference designate corresponding parts in all the views, and in which:

Figure 1 is a perspective view of a hook member and an eye member showing the same in relative engagement; Fig. 2 is a perspective view of the hook member and eye member showing the same in disconnected position; Fig. 3 is a fragmentary transverse sectional view of portions of a garment showing one manner of mounting our device thereon, the hook and eye members being in connected position; and Fig. 4 is a fragmentary transverse sectional view of portions of a garment showing another manner of mounting our device thereon, the hook and eye members being in connected position.

Referring more particularly to the views, we employ a hook member 10, preferably formed of a single piece of spring-like ma-

terial such as wire or the like, the said piece of wire being bent to form an elongated loop 11 constituting a guide 12, the mentioned piece of wire being then bent so that adjacent shanks 13 and 14 of the wire form a hook-like locking member 15, the ends 16 and 17 of the said piece of wire being then bent in opposite directions, to form attaching members 18 and 19, the said attaching members being similar in shape and construction and adapted to lie adjacent one another as shown in Figs. 1 and 2, the guide 12 being offset from the longitudinal plane 60 of the shanks 13 and 14 with the inner extremity of the locking member 15 offset in an opposite direction to the longitudinal plane of the shanks 13 and 14, as shown, the attaching members 16 and 17 being 65 adapted to lie in the plane of the forward ends of the shanks 13 and 14 and adjacent the extremities of the guide 12.

An eye member 20 is employed and consists of a single piece of spring-like material such as wire, the said piece of material being bent to form a wedge-like member 21 having an apex 22 and inclined sides 23, the ends 24 and 25 of the said piece of wire being then bent to extend toward one another and then bent rearwardly to form adjacent shanks 26 and 27, bent at their extremities in opposite directions to form attaching members 28, 29, it being readily seen by referring to the views that the wedge 80 member 21 and attaching members 28 and 29 of the eye member 20 lie in the same plane, the guide 12 of the hook member 10 and the locking member 15 of the hook member 10 being offset in the same direction 85 from the general plane of the hook member.

As shown in Fig. 3, the hook member 10 is secured to a portion 30 of a garment and the eye member 20 is secured to a portion 31 of the garment. Now when it is desired 100 to bring the ends 32 and 33 of the respective portions 30 and 31 of the garment together, the wedge member 21 is passed through the guide 12, the apex 22 of the wedge member being placed over and sprung into engagement with the locking member 15 of the hook member 10, it being readily understood 105 that the resiliency or spring-like action of the eye member 20 and the particular shape of the wedge member 21 will permit of springing the apex 22 of the wedge member 21 into engagement with the locking member 15 when the sides 23 of the wedge member 21 are slightly compressed against the 110

spring-like action of the eye member when the sides 23 engage the sides or ends of the guide 12 of the hook member 10, the mentioned apex 22 being received and held 5 at the inner end of the locking member 15 as shown in Fig. 3. Now it will be readily seen by referring to Fig. 3 that the ends 32, 33 of the portions 30 and 31 of the garment will be held in adjacent position and 10 cannot be separated by pulling the same in opposite directions in view of the manner in which the eye member 20 is engaged with the hook member 10, it being further seen that a lateral pressure exerted against the 15 inner faces of the eye member and hook member will not move or tend to force the eye member out of engagement with the hook member, whereas by simply exerting a slight pressure on the sides 23 of the 20 wedge member 21 of the eye member 20, to move the apex 22 out of engagement with the locking member 15 of the hook member 10, the wedge member 21 will be unlocked from the hook member 10 and can then 25 easily be disengaged therefrom by pulling the portions 30 and 31 of the garment in opposite directions.

It should be noted that the successful operation of the device described depends 30 largely upon the particular shape and construction of the wedge member 21 and the spring-like action of both the hook member 10 and the eye member 20, thus making it 35 decidedly advantageous to form the hook member 10 and the eye member 20 of single pieces of material such as wire, said material being of sufficient resiliency to produce the desired spring-like action in the finished articles.

40 In Fig. 4 we show another manner of employing the device in connection with the portions 30 and 31 of a garment and in which the hook member is secured to the inner side of the portion 30 and the eye 45 member to the outer side of the portion 31, the eye member being secured to the outer side of the portion 31 immediately adjacent the end 33 thereof and the hook member being secured to the inner face of the portion 30 a distance from the end 32 thereof so that when the eye member is connected and locked to the hook member, the extremity of the portion 30 will overlap those parts 50 of the eye member which are secured to the outer face of the portion 31, thus partially inclosing the eye member between the portions 30 and 31 so that the hook and eye 55 will not be visible to the casual observer.

It should be noted that by employing an 60 elongated guide 12 forming a part of the hook member 10 and a wedge member 21 on the eye member 20, said wedge member being adapted to engage the ends of the guide

12 when the eye member is connected to the hook member, contact surfaces of greater 6 area than the usual hook and eye now employed are provided, and where in the usual hook and eye there is only one point of connection or contact between the hook member and the eye member, with the device described there are substantially three points 70 of contact between the hook member and the eye member, the sides 23 being in contact with the ends of the guide 12 and the apex 22 having locked connection with the locking member 15, it being readily seen that the rearmost portion of the wedge member 21 is 75 of a greater width than the guide 12 in that the sides of the wedge member may be slightly compressed against the spring-like 80 action of the wedge member when the wedge member is passed through and engaged with the guide 12, the increase in width of the wedge member over the guide member being also provided to prevent the wedge member 85 from entirely passing through the guide member, thus preventing the eye member 20 from being securely locked to the hook member 10. At the point where the locking member 15 is formed by the shanks 13 and 14 90 of the piece of wire constituting the hook member 10, the portions of the wire between the extremities of the locking member 15 are bent upon the shanks 13 and 14 so that the inner extremity of the locking member 95 15 will be a shorter distance from the guide 12 than the outer extremity of the locking member, this construction being provided to retain the apex 22 of the wedge member 21 in locked position on the hook member 10. 100

Having thus described our invention, we claim:

In a hook and eye, the combination with a hook member formed of a single piece of material bent upon itself to form an elongated guide, and thence bent at a point medially of the guide and rearwardly therefrom to form a locking member, the ends of said piece of material terminating in offset attaching members, of an eye member formed 105 of a single piece of material bent to form a wedge member, the said piece of material being then bent to form attaching members, said wedge member being adapted to be passed through the said guide to engage 110 the said locking member and retaining the eye member in rigid and locked engagement with the hook member.

In testimony whereof we affix our signatures in presence of two witnesses.

ALBERT P. FULMER.
